UNITED STATES PATENT OFFICE.

CARL F. MEAD, OF CLEVELAND, OHIO.

SIGNALING SYSTEM.

1,249,162.

Specification of Letters Patent.

Patented Dec. 4, 1917.

Application filed September 16, 1912. Serial No. 720,518.

To all whom it may concern:

Be it known that I, CARL F. MEAD, a citizen of the United States, residing at Cleveland, in the county of Cuyahoga and State of Ohio, have invented certain new and useful Improvements in Signaling Systems, of which the following is a specification.

This invention relates to improvements in signaling systems and also to contact devices for such systems, and particularly to that class of such devices utilized in the signaling in offices, factories and banks.

More specifically the invention relates to an improvement over the system and construction set forth in my Patent No. 1,164,737, granted December 21, 1915, and contemplates certain features which render the device positive and more efficient generally.

20 The invention may be more briefly summarized as consisting in the construction and combination of parts hereinafter set forth in the following description, drawings and claims.

25 Referring to the drawings, Figure 1 is a front elevation of the machine; Fig. 2 is a top plan view; Fig. 3 is a detail sectional view; Fig. 4 is an end elevation; Fig. 5 is a transverse sectional view through the device showing the arrangement of parts; Fig. 6 is a detail view of portions of the device shown in elevation; Fig. 7 is a detail view showing the gearing connected to the driving pulley; Fig. 7^a is a diagrammatic view 30 showing the arrangement of the signaling system; Fig. 8 is a view of the bells utilized and the mechanism for sound bells; Fig. 9 is a view partly in section showing the top of relay; and Fig. 10 is a section upon the line 40 10—10 of Fig. 8.

In carrying out the invention any preferred form and construction of parts may be employed so long as they possess the necessary characteristics, but I have shown 45 one embodiment in the drawings which is highly effective in operation, and in such disclosure 1 represents a suitable base, to which is secured a pair of upright frame members 2 and 3 as shown in Figs. 1 and 2. 50 These members support the mechanism and also support a casing which is not shown.

Secured to the frame members 2 and 3 is a frame 4 having bracket members 5 and 6 which extend down inside of the frame 55 members to support the mechanism. Each of the brackets is provided with a down-

wardly extending arm 7 Figs. 4 and 5 provided with threaded openings 8 for receiving screws 9 Fig. 3 which pass through fiber bearing blocks 10. These blocks support a 60 commutator shaft 11 extending across the machine and out beyond each of the arms 7. On the right hand side of the machine, as shown in Fig. 1, this shaft is provided with a gear wheel 12 meshing with a pinion 13 65 mounted upon a shaft 14 supported in eccentric openings in fiber or other insulating bearings 15 and 16, threaded in a bracket 17 on one side and in one of the arms 7 on the other as shown in Fig. 7. The shaft 14 70 carries a driving pulley 18 driven by a belt 19 from a driving pulley 20 secured to the shaft of a motor 21.

Mounted upon the shaft 11 is the commutator member comprising a plurality of 75 disks 22 having mounted between them rods or contact members 23, and these rods or contact members form between the disks contacts corresponding to the several signals which the machine is intended to give. 80 The disks 22 are held in place by means of sleeves 24 mounted upon the shaft between adjacent disks, all of the sleeves and the disk being held in place by end disks 25, each of which is provided with a hub 26 secured to the shaft 11 by a set screw 27.

Coöperating with the rods or contact members 23 which extend between the disks are a plurality of contact levers or keys, one for each signal, and each comprises a 90 lever 28 mounted upon a common shaft 29 supported in the frame. Each of the levers is provided with an operating rod 30 extending out to the front of the machine and through a slot 31 in a face plate 32 95 and also through a compound slot 33 in a locking plate 34 mounted in a guiding frame 34 secured to the framework of the machine as shown in Figs. 1, 2, 4 and 5. The compound slot comprises a diagonal 100 portion and a horizontal portion, the two portions being in communication, and the rod normally assuming a position in the horizontal portion, where it merges into the diagonal portion so that when the rod is 105 moved down, the plate is engaged by it and shifted longitudinally, the horizontal portion of the slot receiving the rods 30 of the other keys and preventing their downward movement. Each of the levers 28 is normally held in an elevated position by means of a spring 35 secured at one end to the rod 110

and at the other end to the frame. Each contact lever 28 carries a block 36 preferably formed integral with the lever and having secured to it and insulated from it 5 a leaf contact 37 having a portion extending down below the lever and to a point where it is out of the path of the corresponding rods or contact members 23 when the contact lever is elevated but is adapted to 10 move into the path of such rods when the lever is depressed. The upper portion of the leaf contact extends up above the lever and engages a contact bar 38 secured to but insulated from the supporting frame 34' 15 which supports and guides the locking plate 34 as set forth in Fig. 5. The locking plate 34 is normally held in a position to the left, as shown in Fig. 1 by means of a spring 39 Fig. 1 secured at one end to the plate 20 and at the opposite end to the framework 34'. The position of this plate therefore is such that the rods of all the contact levers are at the merging point of the two portions of the slot formed in the locking plate. 25 Current is supplied to the shaft 11 through springs 40 Figs. 3 and 5 arranged in openings 41 in the friction bearing blocks 10, and screws 42 hold these springs under tension against the shaft, and at the same 30 time hold the wire which forms a part of the circuit.

Suitable means is provided for normally holding the contact lever depressed, and this mechanism is connected to the locking plate 34 and it comprises a switch lever 43 pivoted to the frame 34' and connected above the center as at 43' to the locking plate 34. At its lower end it carries a lug 44 engaging the side face of a cam disk 45 shown clearly in Fig. 4. This cam disk is 35 cut out to form a cam face 46 and an abrupt shoulder 47. Upon the shifting of one of the contact levers the plate 34 is shifted to the right, causing the lever 43 to be moved 40 in a clockwise direction as shown in Fig. 1, thereby carrying the lug 44 out to a point where it will engage the side face of the cam disk so that if the disk were rotated the lug would ride upon the side face of the 45 disk and hold the locking plate 34 to the right, and since the rods of all of the contact levers, except the one depressed move into the horizontal portion of the corresponding slot in the locking plate all of the 50 levers will be locked in position, and none of them can be depressed during the giving of a signal. The cam disk 45 is rigidly secured to the shaft 11 so that it will rotate therewith. 55 It is essential that the motor should start the rotation of the driving mechanism and the shaft 11, upon the downward movement of a contact lever, and this is brought about by suitable switch mechanism arranged in conjunction with the lever 43, and 60

it comprises an insulating block 47' secured to the upper end of the lever 43 and carrying a contact pin 48 adapted to pass between the leaf spring contacts 49 and complete the circuit to the motor. From the foregoing it will be seen that upon the depression of a contact lever, the sliding plate 34 is shifted to the right and the lever 43 is rocked in a clockwise direction, causing its lug 44 to be moved out to a point where it 75 can engage the side face of the cam disk with the result that the contact pin 48 is thrust into engagement with the leaf spring contacts when the motor is started. Upon the operation of the motor, however, the 80 shaft 11 is rotated as the lug 44 rests upon the side face of the cam disk 45 so that the circuit to the motor is kept closed during the rotation of the shaft 11. In the meantime, the contact rods 23 have engaged 85 the leaf contact carried by the depressed contact lever and the contact through the signaling circuit has been broken and closed to give the proper signal. Upon a complete revolution of the shaft 11, the lug 44 drops 90 off at the shoulder 47 and permits the locking plate to be shifted to the left or normal position when the depressed key will be returned. The machine is then ready for another operation. 95

In case the operator should desire to repeat a signal the device is provided with an extra key 50 secured to a shaft 51 passing through the frame member 2 and having a bearing in one of the arms 7. This shaft 100 carries a dog 52 shown in Fig. 6, which is adapted to be moved by the rotation of the shaft 51 into engagement with the lever 43 so as to hold it in position so that the plate 34 is held to the left. 105

The system as shown in the diagrammatic view in Fig. 7^a, comprises a main line circuit consisting of wires 53 and 54, branches 55 and 56 of which lead to the signal contact device already described. A line comprising the wires 57 and 58 lead from the signal contact device to an alarm circuit in which are placed the signals which may be in the form of bells 59, as shown, or they may be lights. 110

If it is desired to extend the system beyond the capacity of a single line for taking care of the signals, a line comprising wires 61 and 62 may be led to a relay 63 which is supplied with current from a line comprising wires 64 and 65 from the main circuits 53 and 54, and an alarm circuit 66 and 67 may be led to a plurality of bells 60 or other devices. In this way, the system may be extended over large factories and plants with 115 a single central signaling contact device. 120

The form of bell utilized is of a solenoid type and comprises a base 68 having secured thereto a suitable housing 69 having an opening 70 at the end nearest the bell and in 130

alinement with this opening and at the bottom, an adjusting socket member 71 comprising a thumb piece 72 extending outside of the housing, and an internally threaded portion which receives a nut 73 having an opening therein and a transverse bar 74 across the opening, see Fig. 10. This transverse bar engages in a slot 75 formed in a brass tube 76 upon which is mounted the 10 solenoid coil 77. This tube receives the armature or core 78 which rests upon the cross bar 74. This core has at its upper end a suitable striker 79. By the arrangement of the parts, it will be seen that when current 15 passes through the coil 77 the solenoid core will be drawn quickly within the coil and the striker 79 will engage the bell. In order to adjust the striker the thumb piece 72 may be rotated and the position of the 20 nut 73 and the cross bar 74 varied within the threaded portion of the socket member 71.

The relay comprises a casing 80 having mounted therein a pair of solenoid coils 81 secured rigidly in the casing and adapted to be connected by a suitable line to the circuit leading from the signal contact device to the first set of signals. Coöperating with these coils 81 are a pair of armature 25 cores 82, both connected to a switch block 83 insulated therefrom and carrying contact members 84 and 85. These two contact blocks engage between pairs of leaf contacts 86 and 87, 88 and 89 respectively. These 30 leaf contacts just referred to are secured to an insulating bar 90 secured to the casing. Supply wires 64 and 65 enter the casing and the former is secured to the leaf contact 87 while the latter is secured to the 35 leaf contact 88. The relay signal circuit comprising the lines 66 and 67 is connected so that one line, for example 66 leads to the contact 89 while the other 67 leads to the contact 86. When the line comprising the 40 wires 61 and 62 receives an impulse from the central signal contact device the solenoid 45 receives an impulse and their cores

82 are drawn inward with the result that the contact bars 84 and 85 are brought into engagement with the leaf contacts 86, 87, 88 and 89 with the result that the circuit formed by the lines 64, 65, 66 and 67 is completed and additional signals are given. 50

In the drawings I have shown the mechanism supported on the frame members 55 2 and 3. This construction may be utilized in connection with a casing covering all of the mechanism, or the mechanism itself may be mounted on the inside of the casing and the reference in the specification to the frame 60 is intended to include either of the constructions mentioned.

Having described my invention, I claim—

1. An alarm system, comprising a main circuit, a source of current supplying said circuit, a branch circuit, a central signal contact device in said branch circuit, a signal circuit supplied with current from the main circuit, said signal device controlling the currents to said signal circuit through 70 said signal device, an auxiliary independent signal circuit connected to said main circuit, and means under the control of said signal device for controlling the connection to said auxiliary signal circuit. 75

2. An alarm system, comprising a main circuit, a source of current supplying said circuit, a branch circuit, a central signal contact device in said branch circuit, a signal circuit supplied with current from the main circuit, said signal device controlling the current to said signal circuit through 80 said signal device, an auxiliary independent signal circuit connected to said main circuit, and a contact device in said auxiliary signal circuit and under the control of the said signal device for controlling the connection to said auxiliary signal circuit. 85

In testimony whereof I affix my signature in presence of two witnesses as follows:

CARL F. MEAD.
